Joshua Moore's Patent for Straw-Cutter

Letters Patent

The Submitter is forced to inform the Patent Office and the public that of the same containing a description in the words of Plaintiff, Joshua Moore himself of his improvement in a machine for cutting straw
to all whom these presents shall come

Be it known that Joshua Moore of the County of Roane in the State of Tennessee has invented a new machine or a new and useful improvement for cutting straw and that the following is a full and exact description of the construction and operation of the said machine as invented by me.

The Box is in the usual form for cutting straw or hay. The improvement is in having a short knife facing the front of the Box fastened to an upright Iron Bar which is attached to a tridale that works between the front feet of the Box and one end of the tridale is fastened to the left leg of the Box with a spring under it to move it and the other end acting along through the right leg. The Box is faced with wood having a slot or groove in which the knife stays.
